UNITED STATES PATENT OFFICE.

THOMAS A. J. HENDRIX, OF FULTON, WHEELING, WEST VIRGINIA.

BUTTON.

1,410,916.

Specification of Letters Patent. Patented Mar. 28, 1922.

Application filed September 3, 1920, Serial No. 407,836. Renewed September 22, 1921. Serial No. 502,510.

To all whom it may concern:

Be it known that I, THOMAS A. J. HENDRIX, a citizen of the United States, residing at Fulton, Wheeling, in the county of Ohio and State of West Virginia, have invented 5 certain new and useful Improvements in Buttons, of which the following is a specification.

This invention relates to improvements in 10 fastening devices and more particularly to buttons especially adapted for application to garments though not necessarily restricted to such use.

An important object of this invention is 15 to provide a button which may be readily and conveniently applied to a garment or the like without employing a needle and thread as is customary.

A further object of the invention is to 20 provide a button which when applied to a garment or the like will not pull loose as the result of continued strain.

A further object of the invention is to 25 provide a garment button having novel means whereby the body of the same is spaced from the portion of the garment to which it is attached so that the button may be readily engaged with the portion of the garment having the buttonhole.

A further object of the invention is to provide 30 a button of the class described which is simple, neat in appearance, and cheap to manufacture.

Other objects and advantages of the invention will be apparent during the course 35 of the following description.

In the accompanying drawing, forming a part of this application, and in which like numerals are employed to designate like 40 parts throughout the same:

Figure 1 is a plan view of the improved button.

Figure 2 is a central vertical sectional view through the improved button applied,

45 Figure 3 is a perspective of an attaching member embodied in the invention,

Figure 4 is a similar view of an attaching shank embodied in the invention.

In the drawing, wherein for the purpose 50 of illustration is shown a preferred embodiment of the invention, the numeral 5 generally designates the improved button which consists of a disk-like body 6 adapted to be passed through the buttonhole of a garment.

55 As illustrated in Figure 2, the body 6 is formed adjacent its center with an offset

annular portion 7 which surrounds the centrally arranged opening 8 formed in the body. It will be noted, however, that the annular portion 7 is spaced outwardly from 60 the opening so as to form an annular flange 9 about the opening 8, which flange is flatly engaged by the annular laterally projecting flange 10 of an attaching shank 11. When the attaching shank 11 is extended through 65 the opening 8, the flange 10 is disposed beneath the surface of the body 6 by reason of the offset portion 7 which forms a centrally arranged recess in the body. The cylindrical body of the shank 11 has its forward end beveled as indicated at 14 so as to readily pass through the opening 8 and so as to spread the inwardly extending prongs 70 or gripping members 16 of the upstanding annular side wall 17 of the body plate 18. 75

The upstanding annular side wall 17 of the plate 18 surrounds a centrally arranged opening 20 which is adapted for the reception of the cylindrical body of the shank 11. By reason of the fact that the upstanding side 80 wall 17 of the attaching plate is provided with a plurality of transverse incisions 22 the cylindrical body of the shank 11 may spread the wall 17 so that the inwardly extending prongs or gripping members 16 may 85 be received within an annular groove 24 in the body of the shank. As illustrated in Figure 2, the annular groove 24 is approximately V-shaped in cross section and the side walls of the same are inclined in the direction of the flange 10 so that the prongs 16 are prevented from accidental displacement. 90 The plurality of arcuate gripping portions formed by the transverse incisions 22 surround the body of the shank 11 and securely 95 engage the same upon the entrance of the body of the shank into the opening 20.

In applying the improved button, the attaching plate or body 18 is arranged on the inner side of a portion of the garment or other material and the upstanding side wall 17 is passed through an opening formed 100 in the material. The body 6 of the button may now be arranged on the outer side of garment with the opening 8 of the same 105 aligned with the opening 20 in the attaching body so that the cylindrical body of the shank 11 may be passed through the opening 8 and into the opening 20. The movement of the shank into the opening 20 causes the 110 arcuate gripping members of the upstanding side wall to be spread slightly and subse-

quently enter the annular groove 24, whereupon the shank will be securely connected to the attaching body or plate. It will be observed that the material of the garment is confined between the flange 9 and the attaching plate 18 and a space remains between the major portion of the body 6 and the material of the garment. This prevents crowding of the material having the button hole and allows the button to be readily connected to the material. It is, therefore, apparent that the offset portion 7 in addition to forming a recess in the outer portion of the body serves as a means for spacing the major portion of the button from the material to which it is attached whereby the button may be readily connected to a piece of material.

It is to be understood that the form of the invention herewith shown and described is to be taken as a preferred example of the same and that such minor changes in arrangement and construction of parts may be made as will remain within the spirit of the invention and the scope of what is claimed.

Having thus described the invention, what is claimed as new is:

1. A button comprising a body having an opening and an offset portion surrounding said opening and forming a recess and a flange, an attaching shank extending through said opening and having a flange arranged within said recess and flatly engaging said first named flange, and an attaching body engaged with said shank.

2. A button comprising a body having an opening, a shank extending through said opening and provided with a flange engaging the adjacent portion of the body, said body being provided with a recessed portion about said shank whereby said flange is disposed beneath the surface of the body, and an attaching body engaged with said shank.

3. A button comprising a body having an opening and an offset portion surrounding said opening and forming a recess and a flange, said flange being adapted to flatly abut the material to which the button is connected, a shank extending through said opening, and an attaching body connected with said shank, said offset portion of said body spacing the major portion of the body from the material to which the button is connected.

4. A button comprising a body having an opening, a shank extending through said opening and engaging said body, and an attaching plate having an upstanding annular side wall provided with a plurality of inwardly extending gripping elements engaging said shank.

5. A button comprising a body provided with a shank, and an attaching plate provided with an upstanding side wall formed of a plurality of arcuate sections having means engaging said shank, the forward portion of said shank being beveled.

6. A button comprising a body having a shank, and an attaching body having a centrally arranged opening and an upstanding annular side wall surrounding said opening and provided with inwardly extending gripping members, said shank being provided with an annular groove adapted to receive said gripping members.

7. A button comprising a body provided with a shank having its forward portion beveled, a body provided with a plurality of arcuate sections having inwardly extending terminal portions beveled at their ends, said shank being provided with a groove adapted to receive the terminal portions of said arcuate sections, said groove having inclined side walls.

In testimony whereof I affix my signature. 85
THOMAS A. J. HENDRIX. [L.S.]
